DOOR LATCH

Stanley D. Cockburn, Warren, Mich., assignor to General Motors Corporation, Detroit, Mich., a corporation of Delaware

Filed Apr. 20, 1960, Ser. No. 23,541
13 Claims. (Cl. 292—279)

This invention relates to a door latch, and more particularly to an improved door latch for an automobile.

One feature of the invention is that it provides an improved door latch.

Another feature of the invention is that it provides a door latch which is substantially smaller in size than other known latches and yet which incorporates all the desirable features of an automobile door latch, including automatic undogging and keyless locking.

Still a further feature of the invention is that it provides a door latch in which a rotary bolt, a detent and a detent release member are coaxially mounted on a common mounting shaft.

A further feature of the invention is that it provides a door latch having a rotatable bolt and a detent mounted coaxially with the bolt, the detent being movable axially between coupled and uncoupled relation with the bolt.

Yet another feature of the invention is that it incorporates a ratchet coupling the bolt to the detent to permit the door to close.

Other features and advantages of the invention will be apparent from the following description and from the drawings, in which:

FIGURE 1 is a fragmentary side elevational view of an automobile incorporating an improved door latch, parts which underlie the door outer panels being shown in broken lines;

FIGURE 2 is an enlarged transverse vertical section through the front door latch of FIGURE 1, being taken along the line 2—2 of FIGURE 1;

FIGURE 3 is a horizontal section through the latch, being taken along the line 3—3 of FIGURE 2;

FIGURE 4 is a vertical section through the latch, being taken along the line 4—4 of FIGURE 2 and showing the detent coupled to the bolt;

FIGURE 5 is a horizontal section taken along the line 5—5 of FIGURE 2, part of the operating shaft being broken away;

FIGURE 6 is a view similar to FIGURE 4, but showing the detent uncoupled from the bolt;

FIGURE 7 is a section taken along the line 7—7 of FIGURE 6;

FIGURE 8 is a view similar to FIGURE 6 taken along the line 8—8 of FIGURE 7;

FIGURE 9 is an exploded view of the bolt and detent showing the ratchet coupling means;

FIGURE 10 is an isometric view of the latch removed from the case;

FIGURE 11 is an exploded isometric view of the latch; and

FIGURE 12 is an isometric view of the latch in the case.

Referring now more particularly to the drawings, the reference character 10 designates an automobile having a front door 12 hingedly mounted at its front edge on the automobile body in conventional manner (not shown) and carrying a latch which is designated generally as 14 and which is mounted adjacent the rear edge of the door. The automobile also has a rear door 16 which is hingedly mounted at its front edge on a body center pillar in conventional manner (not shown) and which, adjacent its rear edge, mounts a latch designated generally as 18.

The front door has a conventional gripping handle

2

20 which is bolted to the door outer panel and which mounts a slidable push button 22 for operating the latch from the outside. A conventional turn handle 24 is mounted on the inner door panel at a location remote from the latch 14 and is connected to the latch by a rod 26. In order to lock the door from the outside there is a conventional key cylinder 28 mounted in the door outer panel below the handle 20 and having a key-operated shaft 29 which is connected to a locking device in the door latch. To lock the door from the inside of the automobile body there is a garnish molding button 30 projecting from the garnish molding of the front door and connected to the latch 14 by a rod 32.

The rear door is generally similar except for the omission of an outside locking means. On the rear door there is a gripping handle 34 which mounts a slidable push button 36 for operating the latch from outside of the car. A turn handle 38 on the door inner panel is connected by a rod 40 to the rear door latch 18 and an inside locking device includes a conventional garnish molding 42 connected by a rod 44 to a bell crank 46 which in turn is connected by a rod 48 to the latch 18.

Inasmuch as the front and rear door latches 14, 18 are generally similar in construction, only the front door latch 14 is shown and described in detail.

The front door latch 14 is adapted to cooperate with a striker 50 which comprises a mounting portion 52 that is bolted to the body center pillar adjacent the door latch and which has a bent portion forming a striker bar 54 having two upstanding teeth 56 for cooperation with the latch bolt in a manner later to be described. The latch 14 has a frame which houses all of the latch parts except the bolt and a portion of the outside operating shaft and which includes a main casing portion 58 that is bolted to the jamb face of the door on the inner surface thereof. Inside the door the case is closed by a cover plate 60. The bolt projects out of the case 58 through an opening in the jamb face of the door and into a bolt housing 62 which is secured to the case 58 and which projects out beyond the outer surface of the jamb face of the door. In addition to encasing the bolt, the housing 62 in its lower portion seats a conventional spring biased sliding shoe 64 which, when the door is closed, bears against the lower surface of the striker bar 54 to provide a dovetail and hold the door against up and down movement.

The heart of the latch 14, and the feature which results in substantially smaller overall size of the latch when compared with other automobile door latches, is an arrangement whereby a bolt designated generally as 66, a detent designated generally as 68 and a detent release member designated generally as 70 are all mounted coaxially on a short mounting shaft designated generally as 72 which is nonrotatably supported in the latch frame or casing between the face of the bolt housing 62 and the cover plate 60.

The bolt 66 is rotatably mounted on a reduced end portion 74 of the mounting shaft 72, and the bolt comprises a gear portion 76 having a plurality of peripheral latching teeth 78 for engagement with the striker teeth 56 when the door is closed and a face plate 80 which preferably is formed integrally with the gear portion 76 of the bolt and which has on its end face a plurality of ratchet teeth 82. The bolt 66 is rotatable on the mounting shaft portion 74 and is retained on the shaft by the outer face of the bolt housing 62.

The detent, which is designated generally as 68, is slidably but nonrotatably mounted on the enlarged center portion 84 of the mounting shaft 72, being held against rotation relative to the mounting shaft by a detent cam follower pin 86 which is mounted in upper and lower openings 88 formed in a cup-shaped portion 89 of the

detent and which projects through an elongated longitudinally extending slot 90 which is formed in the enlarged center portion 84 of the mounting shaft 72. The assembly including the detent and the mounting shaft is held against rotation by two studs 138a and 138b which project through oppositely disposed slots in the lock casing, as indicated in FIGURES 2, 3 and 12. The enlarged body portion 93 of the detent has formed in its face 92 which is adjacent the bolt face 80, a plurality of ratchet teeth 91 which are complementary to the bolt ratchet teeth 82 and which, when they engage with the bolt ratchet teeth 82, serve to hold the bolt against rotation in an unlatching or door opening direction. A coil spring 95 seats between the inner surface of the enlarged body 93 of the detent and a shoulder formed on the detent release member 70 to yieldably urge the detent toward the bolt so that the detent ratchet teeth 91 are normally in coupled engagement with the bolt ratchet teeth 82 to hold the bolt against rotation in an unlatching or door opening direction.

When the door is being closed, the bolt rotates as its latching teeth 78 ride over the teeth 56 of the striker. The ratchet arrangement between the bolt and the detent permits rotation of the bolt in a latching or door closing direction, since as the bolt rotates, its ratchet teeth 82 cam over the sloping back surface of the detent ratchet teeth 91, causing the ratchet to slide on the mounting shaft. In the event the latch parts should be in locked position when the door is being closed, this sliding movement of the detent results in automatic undogging or automatic movement of the latch parts back to unlocked position in a manner later to be described.

The detent release member 70 has a cup-shaped body portion 94 which encases the body portion 89 of the detent. The cup-shaped portion is closed at its base by a gear segment 98 having a plurality of gear teeth 100 formed on its periphery. The gear segment 98 has a central circular opening which receives a circular hub 102 formed near the end of the mounting shaft 72 so that the detent release member is rotatable on the shaft 72. At its end the shaft 72 has a key 104 which is received in a complementary centrally disposed opening in the back plate 60 of the lock casing to hold the shaft 72 against rotation in the casing.

Oppositely disposed triangular openings 106a and 106b are formed in the cup-shaped portion 94 of the detent release member 70 and these openings receive opposite ends of the detent cam follower pin 86. The openings 106a and 106b respectively provide cam surfaces 106c and 106d so that upon rotation of the detent release member in a counterclockwise direction as the parts appear in FIGURE 2, the detent 68 slides on the mounting shaft 72 to uncouple the detent ratchet teeth 91 from the bolt ratchet teeth 82 and permit free rotation of the bolt 66.

In order to provide means for rotating the detent release member 70 to open the door from the outside, there is an operating shaft 108 which is journaled in and projects through opposite side walls of the lock casing 58, the shaft 108 being longitudinally (axially) movable as well as being rotatable relative to the casing. A rack 110 is mounted on the shaft 108 in such a position that the rack teeth 112 normally engage the gear teeth 100, the rack teeth 112 providing drive means and the gear teeth 100 providing driven means for the outside actuator. At its outer end the operating shaft 108 mounts a crank 114 which is connected to the outside key locking means and which is also engaged by the push button operator to cause axial movement of the shaft. A coil spring 116 on the shaft acts to return it to its normal operative position after actuation by the outside push button and a stop abutment 117 on the shaft 108 engages the casing wall to limit return movement of the shaft under force of the spring 116. At its inner end the shaft 108 mounts a crank 118 adapted to be connected to the inside locking means. The shaft also carries an undogging tab 120 which is adapted to cooperate with a complementary un-

dogging member 122 on the detent 68 in a manner later to be described. The push button 22 (FIGURE 1) is connected in conventional manner to a push rod 124 (FIGURE 2) which terminates adjacent the crank 114 so that when the push button is pushed in, the rod 124 pushes the operating shaft 108 to the left in FIGURE 2, causing the rack 110 to move to the left and rotate the detent release member 70 in a counterclockwise direction.

In order to lock the door against outside operation, the operating shaft 108 may be rotated a few degrees in a clockwise direction (FIGS. 4, 6 and 8) to uncouple the rack teeth 112 from the gear teeth 100 so that upon actuation of the outside push button the operating shaft 108 merely "free wheels" and the outside push button is rendered ineffective. This locking rotation of the shaft may be accomplished from the outside through the conventional key lock 28 or from inside of the automobile through the conventional garnish molding button 30. As shown in FIGURE 2, there is a key shaft 29 which is connected at one end in conventional manner (not shown) to the key cylinder and which is connected at the other end to the crank 114. Turning a proper key in the key cylinder serves to rotate the operating shaft 108 through a few degrees of arc to uncouple the rack 112 from the gear teeth 100. The locking rod 32 which extends from the inside garnish molding button is connected to the crank 118 at the inner end of the shaft 108 so that depression of the garnish molding button 32 rotates the shaft 108 to its uncoupled or locked position.

In order to open the door from the inside there is a yoke 130 which is pivotally mounted on a pin 132 extending between the opposite walls of the casing 58. The yoke is formed as a bell crank having first lever arms 134a and 134b for engaging and operating the detent and a second lever arm 136 which is connected to the remote handle operating rod 26. As shown in FIGURE 2, the detent body 92 is formed with outwardly projecting studs 138a and 138b which lie adjacent the respective upstanding lever arms 134a and 134b of the yoke 130 so that when the remote handle 24 is turned to swing the yoke on its pivot, the upstanding arms 134a and 134b pick up the respective detent studs 138a and 138b and shift the detent 68 along the mounting shaft 72 to uncouple the detent ratchet teeth 91 from the bolt ratchet teeth 82 and permit free rotation of the bolt. It should be noted that neither the inside nor the outside locking means affects operation of the latch from the inside of the automobile.

In order to open the latch from outside, the push button 22 is depressed so that the push rod 124 moves the operating shaft 108 axially, the intermeshing gear and rack teeth causing the detent release member 70 to rotate. The cam surfaces 106c and 106d on the detent release member which are in engagement with the detent cam follower pin 86 pull the detent further into the detent release member so that the detent ratchet teeth disengage from the bolt ratchet teeth to permit the bolt to rotate.

To lock the door, either a key is turned to operate the crank 114 or the garnish molding button 30 is depressed to operate the crank 118. In either event the operating shaft 108 with its rack 110 is rotated to uncouple the rack teeth 112 from the gear teeth 100 of the detent release member gear 98 and place the parts in locked condition. With the parts in this condition, operation of the outside push button 22 will merely cause the operating shaft 108 to free wheel. In all cases, when the outside push button 22 is released the spring 116 will return the shaft axially to its normal position, the stop member 117 engaging a wall of the lock casing to limit return movement when the shaft is in its proper position.

The door lock incorporates the features of automatic undogging, remote undogging and keyless locking. Automatic undogging means that if the latch parts are placed in locked position when the door is open, upon closing the door the parts will be shifted back to unlocked posi-

tion. However, if the operator desires to do so, he may lock the door without a key merely by depressing the outside push button 22 while the door is being closed. Remote undogging means that if the door is opened from the inside when the latch parts are in locked position, the parts will be shifted to unlocked position. Assuming that the parts are in locked position as shown in FIGURE 8 and the door is slammed shut, rotation of the bolt 66 as the bolt latching teeth 78 ride over the striker teeth 56 will cause the bolt ratchet teeth 82 to cam over the sloping back side of the detent ratchet teeth 91, sliding the detent on the mounting shaft 72 during this camming action. As the detent slides, its undogging tab 122 will engage the undogging tab 120 on the shaft 108 and rotate the shaft 108 back to its unlocked position. Remote undogging may be accomplished in a similar manner. If the latch parts are in locked position and the door is opened by means of the inside remote handle 24, the detent 68 will be moved along the shaft 72 out of coupled relation with the bolt. During this movement the detent undogging tab 122 will engage the undogging tab 120 on the operating shaft 108 and rotate the shaft back to its unlocked position. Automatic undogging may be avoided and keyless locking may be accomplished by depressing the outside push button 22 while the door is being closed. If this is done the undogging tab 120 will be moved to the left (FIGURE 2) out of the path of movement of the undogging tab 122 so that the shaft 108 will not be rotated to its unlocked position.

While I have shown and described one embodiment of my invention, it is capable of many modifications. Changes, therefore, in the construction and arrangement may be made without departing from the spirit and scope of the invention, as set forth in the appended claims.

I claim:

1. A vehicle door latch of the character described, including: a mounting shaft; a bolt rotatably mounted on said shaft and having a plurality of ratchet teeth on an end face thereof and a plurality of peripheral latching teeth; a detent slidably but non-rotatably mounted on said shaft, said detent having a plurality of ratchet teeth facing the bolt ratchet teeth and normally being coupled thereto to hold the bolt against rotation in one direction; a detent release member rotatably mounted on said shaft; means coupling said detent to said detent release member comprising a cam follower projecting from said detent into engagement with a cam on said detent release member whereby rotation of said detent release member causes said detent to slide on said shaft to uncouple the detent ratchet teeth from the bolt ratchet teeth; and means for rotating said detent release member.

2. A vehicle door latch of the character described, including: a mounting shaft; a bolt rotatably mounted on said shaft and having a plurality of ratchet teeth on an end face thereof and a plurality of peripheral latching teeth; a detent slidably but non-rotatably mounted on said mounting shaft, said detent having a plurality of ratchet teeth facing the bolt ratchet teeth; spring means yieldably urging said detent ratchet teeth into coupled engagement with said bolt ratchet teeth to hold the bolt against rotation in one direction; a detent release member rotatably mounted on said shaft; means coupling said detent to said detent release member comprising a cam follower on said detent and a cam on said detent release member, the cam follower projecting from said detent into engagement with said cam whereby rotation of said detent release member causes said detent to slide on said mounting shaft to uncouple the detent ratchet teeth from the bolt ratchet teeth; and outside latch operating means for rotating said detent release member.

3. A vehicle door latch of the character described, including: a mounting shaft; a bolt rotatably mounted on said shaft and having a plurality of ratchet teeth on an end face thereof and a plurality of peripheral latching teeth; a detent slidably but non-rotatably mounted on

said mounting shaft, said detent having a plurality of ratchet teeth facing the bolt ratchet teeth; spring means yieldably urging said detent ratchet teeth into coupled engagement with said bolt ratchet teeth to hold the bolt against rotation in one direction; a detent release member rotatably mounted on said shaft; means coupling said detent to said detent release member comprising a cam follower on said detent and a cam on said detent release member, the cam follower projecting from said detent into engagement with said cam whereby rotation of said detent release member causes said detent to slide on said mounting shaft to uncouple the detent ratchet teeth from the bolt ratchet teeth; outside latch operating means for rotating said detent release member; and inside operating means comprising a lever engaging said detent and adapted upon actuation to slide said detent on said mounting shaft to uncouple the detent ratchet teeth from the bolt ratchet teeth.

4. A vehicle door latch of the character described, including: a mounting shaft; a bolt rotatably mounted on said shaft and having a plurality of ratchet teeth on an end face thereof and a plurality of peripheral latching teeth; a detent slidably but non-rotatably mounted on said mounting shaft, said detent having a plurality of ratchet teeth facing the bolt ratchet teeth; spring means yieldably urging said detent ratchet teeth into coupled engagement with said bolt ratchet teeth to hold the bolt against rotation in one direction; a detent release member rotatably mounted on said shaft; means coupling said detent to said detent release member to slide the detent on said shaft to uncouple the bolt ratchet teeth from the detent ratchet teeth upon rotation of said detent release member; and means for rotating said detent release member, comprising driven means on said detent release member and a longitudinally movable and rotatable operating shaft having drive means normally coupled to said driven means; and latch operating means for moving said operating shaft longitudinally to rotate said detent release member.

5. Apparatus of the character claimed in claim 4, wherein said driven means comprises a gear on said detent release member and said drive means comprises a rack on said operating shaft.

6. A vehicle door latch of the character described, including: a mounting shaft; a bolt rotatably mounted on said shaft and having a plurality of ratchet teeth on an end face thereof and a plurality of peripheral latching teeth; a detent slidably but non-rotatably mounted on said mounting shaft, said detent having a plurality of ratchet teeth facing the bolt ratchet teeth; spring means yieldably urging said detent ratchet teeth into coupled engagement with said bolt ratchet teeth to hold the bolt against rotation in one direction; a detent release member rotatably mounted on said shaft; means coupling said detent to said detent release member whereby rotation of said detent release member causes said detent to slide on said shaft to uncouple the detent ratchet teeth from the bolt ratchet teeth; means for rotating said detent release member, comprising a gear on said detent release member and a longitudinally movable and rotatable operating shaft having a rack normally coupled to said gear; outside latch operating means for moving said operating shaft longitudinally to rotate said detent release member; inside latch operating means comprising a lever engaging said detent and movable upon actuation to cause said detent to slide on said mounting shaft to uncouple the detent ratchet teeth from the bolt ratchet teeth; and locking means for rotating said operating shaft from unlocked to locked position to uncouple the rack from the gear and render the outside latch operating means ineffective.

7. Apparatus of the character claimed in claim 6, wherein the means coupling the detent to the detent release member comprises a pin on said detent and a cam on said detent release member, the pin projecting from the detent into engagement with the cam whereby rotation

of said detent release member causes said detent to slide on said mounting shaft to uncouple the detent ratchet teeth from the bolt ratchet teeth.

8. Apparatus of the character claimed in claim 7, wherein said mounting shaft has an elongated slot into which said pin projects to hold the detent and mounting shaft against relative rotation but to permit sliding movement of the detent on the shaft.

9. In a vehicle having body and door members, a toothed striker mounted on one member, a latch mechanism mounted on the other member and comprising, a mounting shaft; a bolt rotatably mounted on said shaft and having a plurality of ratchet teeth on an end face thereof and a plurality of peripheral latching teeth for engagement with said toothed striker when the door is closed; a detent slidably but non-rotatably mounted on said mounting shaft, said detent having a plurality of ratchet teeth facing the bolt ratchet teeth; spring means yieldably urging said detent ratchet teeth into coupled engagement with said bolt ratchet teeth to hold the bolt against rotation in one direction; a detent release member rotatably mounted on said shaft; means coupling said detent to said detent release member whereby rotation of said detent release member causes said detent to slide on said mounting shaft to uncouple the detent ratchet teeth from the bolt ratchet teeth; means for rotating said detent release member comprising driven means on said detent release member and a longitudinally movable and rotatable operating shaft having drive means normally coupled to said driven means; latch operating means for moving said operating shaft longitudinally to rotate said detent release member; locking means for rotating said operating shaft from unlocked to locked position to uncouple the drive means from the driven means and render the latch operating means ineffective; and undogging means having a first portion on said detent and a second portion on said operating shaft, the first portion striking the second portion upon sliding movement of said detent when the door closes to rotate the operating shaft from locked to unlocked position, the bolt ratchet teeth camming over the detent ratchet teeth when the door closes to slide said detent on said mounting shaft, said second portion of the undogging means being moved out of the path of movement of said first portion of the undogging means when said latch operating means is actuated to move said operating shaft longitudinally.

10. In a vehicle having body and door members, a toothed striker mounted on one member, a latch mechanism mounted on the other member and comprising, a mounting shaft; a bolt rotatably mounted on said shaft and having a plurality of ratchet teeth on an end face thereof and a plurality of peripheral latching teeth for engagement with said toothed striker when the door is closed; a detent slidably but non-rotatably mounted on said mounting shaft, said detent having a plurality of ratchet teeth facing the bolt ratchet teeth; spring means yieldably urging said detent ratchet teeth into coupled engagement with said bolt ratchet teeth to hold the bolt against rotation in one direction; a detent release member rotatably mounted on said shaft; means coupling said detent to said detent release member comprising a cam follower on said detent and a cam on said detent release member, the cam follower projecting from said detent into engagement with said cam whereby rotation of said detent release member causes said detent to slide on said mounting shaft to uncouple the detent ratchet teeth from the bolt ratchet teeth; inside latch operating means comprising a lever engageable with said detent and adapted upon pivotal movement thereof to slide said detent on said mounting shaft to uncouple the detent ratchet teeth from the bolt ratchet teeth; means for rotating said detent release member, comprising driven means on said detent release member and a longitudinally movable and rotatable operating shaft having drive means normally coupled to said driven means; outside latch operating means for

moving said operating shaft longitudinally to rotate said detent release member; locking means for rotating said operating shaft from unlocked to locked position to uncouple the drive means from the driven means and render the outside latch operating means ineffective; and undogging means having a first portion on said detent and a second portion on said operating shaft, the shaft portion striking the second portion upon sliding movement of said detent when the door closes to rotate the operating shaft from locked to unlocked position, the bolt ratchet teeth camming over the detent ratchet teeth when the door closes to slide said detent on said mounting shaft.

11. In a vehicle having body and door members, a toothed striker mounted on one member, a latch mechanism mounted on the other member and comprising, a mounting shaft; a bolt rotatably mounted on said shaft and having a plurality of ratchet teeth on an end face thereof and a plurality of peripheral latching teeth for engagement with said toothed striker when the door is closed; a detent slidably but non-rotatably mounted on said mounting shaft, said detent having a plurality of ratchet teeth facing the bolt ratchet teeth; spring means yieldably urging said detent ratchet teeth into coupled engagement with said bolt ratchet teeth to hold the bolt against rotation in one direction; a detent release member rotatably mounted on said shaft; means coupling said detent to said detent release member comprising a pin on said detent and a cam on said detent release member, the pin projecting from said detent into engagement with said cam whereby rotation of said detent release member causes said detent to slide on said mounting shaft to uncouple the detent ratchet teeth from the bolt ratchet teeth; means for rotating said detent release member comprising a gear on said detent release member and a longitudinally movable and rotatable operating shaft having a rack normally coupled to said gear; latch operating means for moving said operating shaft longitudinally to rotate said detent release member; locking means for rotating said operating shaft to uncouple from unlocked to locked position the gear from the rack and render the latch operating means ineffective; and undogging means having a first portion on said detent and a second portion on said operating shaft, the first portion striking the second portion upon sliding movement of said detent when the door closes to rotate the operating shaft from locked to unlocked position, the bolt ratchet teeth camming over the detent ratchet teeth when the door closes to slide said detent on said mounting shaft, said second portion of the undogging means being moved out of the path of movement of said first portion of the undogging means when said latch operating means is actuated to move said operating shaft longitudinally.

12. In a vehicle having body and door members, a toothed striker mounted on one member, a latch mechanism mounted on the other member and comprising, a mounting shaft; a bolt rotatably mounted on said shaft and have a plurality of ratchet teeth on an end face thereof and a plurality of peripheral latching teeth for engagement with said toothed striker when the door is closed; a detent slidably but nonrotatably mounted on said mounting shaft, said detent having a plurality of ratchet teeth facing the bolt ratchet teeth; spring means yieldably urging said detent ratchet teeth into coupled engagement with said bolt ratchet teeth to hold the bolt against rotation in one direction; a detent release member rotatably mounted on said shaft; means coupling said detent to said detent release member comprising a pin on said detent and a cam on said detent release member, the pin projecting from said detent into engagement with said cam whereby rotation of said detent release member causes said detent to slide on said mounting shaft to uncouple the detent ratchet teeth from the bolt ratchet teeth, said mounting shaft having an elongated slot into which said pin projects to hold the detent and the mounting shaft against relative rotation but to permit sliding

movement of the detent on the shaft; means for rotating said detent release member, comprising driven means on said detent release member and a longitudinally movable and rotatable operating shaft having drive means normally coupled to said driven means; latch operating means for moving said operating shaft longitudinally to rotate said detent release member; locking means for rotating said operating shaft from unlocked to locked position to uncouple the drive means from the driven means and render the latch operating means ineffective; and undogging means having a first portion on said detent and a second portion on said operating shaft, the first portion striking the second portion upon sliding movement of said detent when the door closes to rotate the operating shaft from locked to unlocked position, the bolt ratchet teeth camming over the detent ratchet teeth when the door closes to slide said detent on said mounting shaft, said second portion of the undogging means being moved out of the path of movement of said first portion of the undogging means when said latch operating means is actuated to move said operating shaft longitudinally.

13. A vehicle door latch of the character described, including: a mounting shaft; a bolt rotatably mounted on

said shaft and having a plurality of ratchet teeth on an end face thereof and a plurality of peripheral latching teeth; a detent slidably but nonrotatably mounted on said shaft, said detent having a plurality of ratchet teeth 5 facing the bolt ratchet teeth; means yieldably urging said detent ratchet teeth into coupled engagement with said bolt ratchet teeth to hold the bolt against rotation in one direction; a detent release member movably mounted on said shaft; means coupling said detent to said detent release member to slide the detent on said shaft to uncouple the bolt ratchet teeth from the detent ratchet teeth upon movement of said detent release member, said last mentioned means also holding the detent and mounting shaft against relative rotation; and means for moving said 10 15 detent release member.
